DECANTER SET OR SIMILAR ARTICLE

Herbert Lagin, Great Neck, N. Y., assignor to Allen Frederic Corp., Bronx, N. Y., a corporation of New York

Application October 14, 1958, Serial No. 52,977

Term of patent 14 years

(Cl. D58—8)

Fig. 1 is a front perspective view of a decanter set embodying my new design; and

Fig. 2 is a cross-sectional view thereof taken along line 2—2 of Fig. 1.

I claim:

The ornamental design for a decanter set or similar article, substantially as shown.
